Application January 31, 1934, Serial No. 709,218
In Great Britain February 21, 1933

6 Claims. (Cl. 74—302)

This invention relates to frictional epicyclic gears and has for its object to improve and simplify the construction of devices of this type in general and to provide improved and simple 5 means for effecting the contact pressure between the various members of the gear.

According to this invention a gear of the type indicated, i. e. comprising a sun member, a series of planets mounted on a carrier and an annulus is characterized in that the sun and the planets are locked against relative axial movement and are bodily movable in axial direction for pressure adjustment relatively to the annulus which has a conical or curved contact surface. 10 By this means independent pressure on the planets axially is avoided, and the liability to excessive strain and distortion on the planet axles and their bearings is obviated.

In one embodiment the arrangement is such 20 that the sun and the planets become interlocked when assembled, no separate members to effect the interlocking being required. For this purpose the sun and the planet carrier may abut and the sun and planets may be made frusto conical with the imaginary apex of the sun on the side opposite to the planet carrier. The sun is thereby wedged between the planets and cannot be moved relatively thereto in the direction of its apex, whilst its movement in the opposite direction 25 is prevented by its abutment against the planet carrier. Or, the contacting surfaces of the sun and the planets may be curved thereby effecting the interlocking of these members against the axial separating movement. If the sun and 30 the planets are not so formed as to effect interlocking against axial separation when these members are assembled then separate fastening or interlocking devices may be added to effect this interlock.

40 Other features of the frictional epicyclic gear according to the invention will appear from the following description.

In the accompanying drawing several embodiments of the gear are shown by way of example:—

Figure 1 is an axial section through a complete gear;

Figures 2, 3, 4 and 5 are fragmentary sectional views of various modified interlocking arrangements between the sun and the planets; and

Figure 6 is a fragmentary front elevation of the planet carrier.

Referring to Figure 1 the annulus 1 is fixedly mounted in the two-part casing 2, 3 which may or may not be rotatable and is held together by

means of screws 4. The parts 2 and 3 of the casing have bosses 5 and 6 respectively. In the boss 5 runs the input shaft 7 on ball bearings 8 and 9 and the output shaft 10 is similarly mounted in boss 6 on ball bearings 11 and 12. In the example shown the sun 13 is integral with the input shaft 7 and the carrier 14 of planets 15 is integral with the output shaft 10. The annulus 1, the sun 13 and the planets 15 have conical contact surfaces and the sun 13 and planet 10 carrier 14 abut, the imaginary apex 16 of the sun 13 being on the side away from the planet carrier 14. Therefore, when the device is assembled axial movement of the sun 13 relatively to the planets 15 in the direction of its apex is prevented because in that direction the sun is wedged between the planets.

In the opposite direction the sun 13 abuts against the planet carrier 14 under the interposition of a thrust bearing 17 and thereby its movement in that direction is prevented.

It will be obvious that any axial pressure applied to the planet carrier 14, as for example by the movement of the adjusting ring 19 via the bearing 11 on to the shoulder of the shaft 10, will be transmitted solidly to the shaft 7 through the bearing 17 on to the shoulder of the sun 13 against which it bears. There can therefore be no possible axial movement relatively between parts of the assembly revolving inside the annulus and its casing.

The sun 13 and the planets 15 are thus interlocked against axial separation when assembled and they can only be moved bodily in relation to the annulus 1 to effect contact pressure adjustment between the latter and the planets. As is well known the correctness of such adjustment is of great importance for the satisfactory operation of the gear as the reduction of slip to the possible minimum and thereby elimination of wasteful and harmful heating up and the load transmitting capacity of the gear depend on the correctness of this adjustment. It has been found that if the pressure adjustment between the sun and the planets is correctly effected when assembling these parts no subsequent adjustment is required between these parts, so that eventual adjustments are confined to that between the planets and the annulus and this, as already mentioned, is effected (in the example shown) by bodily moving the interlocked planets and sun relatively to the annulus.

The axial displacement of the interlocked planets and sun is effected between very fine limits by an externally threaded ring 18 screwed

into the boss 5 and the aforesaid similar ring 19 screwed into the boss 6. These two rings are screwed up tightly on both sides after adjustment has been effected and according to whether reduction or increase of pressure is required between the planets 15 and the annulus 1 one ring is eased and the other tightened up. For pressure reduction, ring 19 is eased and ring 18 tightened up, and for pressure increase, ring 18 is eased and ring 19 tightened up.

For assembling the sun and the planets the sun is caused to abut against the planet carrier 14 under the interposition of thrust bearing 17 and the planet axles 20 are located in their respective slots 21 provided in the periphery of the planet carrier 14 (see also Figure 6). A distance ring 22 is placed between the planets 15 and the carrier 14, the planet axles 20 being secured in position by means of nuts 23 screwed on their threaded rear end under the interposition of locking washers 24 which prevent subsequent turning or unscrewing of the nuts. The planets, when mounted, are caused to abut radially against the sun 13 with the required or correct driving pressure.

Preferably, as shown in Figure 6, between the planet axle slots 21 further radial slots 25 are made in the periphery of the planet carrier 14, so as to form slightly resilient prongs between which the planet axles 20 are received, the resilient flexibility of the carrier 14 enabling the planets to seat themselves with uniform pressure on the sun, and to run with a perfect circumferential balance, i. e. with equal pressure on the annulus and sun at all points of the track. The slots 25 are preferably narrower and deeper than the slots 21.

In Figures 2, 3 and 4 alternative methods of providing interlocking between the planets 15 and the sun 13 are shown. In Figure 2 the sun 13 and the planets 15 have curved contact surfaces so that they are interlocked against relative axial movement when assembled, and the annulus 1 has a conical contact surface. In Figure 3 the arrangement is similar, but the annulus 1 has a convex contact surface. In Figure 4 the planets 15 are balls and the contact surface of the sun 13 is suitably curved, the contact surface of the annulus 1 being conical, although obviously it could be curved as in Figure 3.

In Figure 5 the planets 15 and sun 13 are frustoconical but as distinct from Figure 1 the imaginary apices are located on the side of the system facing the planetary carrier member 14; normally, therefore, when sun and planets are assembled and before inserting this assembly in the casing, they would be able to separate axially. This is prevented by the rings 26 and 27 screwed on to the sun member and planet carrier respectively.

The invention is not limited to the details hereinbefore described. Thus, the sun 13 and the planet carrier 14 need not be integral with the shafts 7 and 10 respectively but may be attached thereto in any suitable manner. The shaft 7 can be the output shaft and the shaft 10 can be the input shaft, in which case a multiplying gear is obtained. The interlocked planets and sun may be secured against axial movement in the casing 70 and the annulus 1 may be constructed so as to

be relatively movable to said interlocked members.

We claim:—

1. An epicyclic gear comprising a driving shaft, a driven shaft axially aligned therewith, a combined journal and end thrust bearing between the inner ends of said shafts holding them in solidly abutting relationship against endwise movement toward each other, a tapered sun gear fixed to one of said shafts, a carrier fixed with respect to the other of said shafts, a series of tapered planet gears carried by said carrier and disposed around and cooperating with said sun gear, a casing in which the solidly abutting driving and driven shafts are journaled for unitary endwise adjustments, a tapered annulus carried by said casing and surrounding said planet gears and cooperating therewith, and means for holding said shafts against relative endwise outward movement and for imparting endwise adjustments to said shafts relative to said casing to vary the pressure between the planet gears and the sun gear and annulus.

2. An epicyclic gear comprising a driving shaft, a driven shaft axially aligned therewith, an end thrust bearing between the inner ends of said shafts holding them against endwise movement toward each other, a tapered sun gear fixed with respect to one of said shafts, a carrier fixed with respect to the other of said shafts, a series of tapered planet gears carried by said carrier and disposed around and cooperating with said sun gear, a casing in which the solidly abutting driving and driven shafts are journaled for endwise adjustments, a tapered annulus carried by said casing and surrounding said planet gears and cooperating therewith, said sun gear and said annulus and said planet gears all being tapered toward a common axial point along the shaft carrying the sun gear, which point is spaced from the inner end of said shaft, whereby the shafts and the sun and planet gears are interlocked for unitary endwise adjustments and whereby such unitary endwise adjustments cause the planet wheels to cooperate with the annulus to vary the pressure between the planet gears and the sun gear and annulus, the shafts being shouldered, and members threaded in said casing and cooperating with the shoulders of said shafts to adjust them axially to vary the pressure between the planet wheels and the sun gear and annulus.

3. An epicyclic gear as set forth in claim 1 in which the carrier is in the form of a disk radially slotted between the points of mounting of the planet gears thereon to provide flexible tongues supporting the planet gears.

4. An epicyclic gear as set forth in claim 2 in which the carrier is in the form of a disk radially slotted between the points of mounting of the planet gears thereon to provide flexible tongues supporting the planet gears.

5. An epicyclic gear as set forth in claim 1 in which the carrier has flexible portions on which the planet gears are mounted.

6. An epicyclic gear as set forth in claim 2 in which the carrier has flexible portions on which the planet gears are mounted.
